TUBE FRAME FOR AXMINSTER LOOMS

Application filed January 7, 1931. Serial No. 507,210.

This invention relates to improvements in Axminster tube frames and it is the general object of the invention to provide such a device with a sliding latch which is substantial in construction and can be readily replaced if damaged.

Axminster looms operate with a plurality of tube frames which are presented one at a time to tuft forming position. The frames are detachably connected to transporting chains by latches which may either be pivoted to or slide on the tube frame. It is usual construction to provide that part of the bracket or hanger of the tube frame which engages the chain with a slot through which the latch extends. It is an important object of my invention to make this part of the bracket solid and to dispose the latch outside of the arm, making the same with two upright portions, one lying on each side of the arm. In this way I provide a bracket having an arm with increased strength.

The brackets may comprise a pair of arms which extend into and are secured to opposite walls of the tube frame carrier bar, and the ends of these arms are bent toward each other to assist in defining a guide for the sliding hook. There is also formed on the bracket a spool bearing which extends upwardly from the carrier bar. It is a further object of my present invention to form the latch with a slot therethrough sufficiently large to receive the spool bearing, to the end that the latch may be slid in a direction away from the chain engaging arm and over the spool bearing for the purposes of removal. The bent ends of the pair of arms extending into the tube frame may be spread apart somewhat to facilitate this removal.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a front elevation of one end of the tube frame made according to my present invention,

Fig. 2 is an end elevation taken in the direction of arrow 2, Fig. 1,

Fig. 3 is a vertical section on line 3—3 of Fig. 2, and

Fig. 4 is a horizontal section on line 4—4, Fig. 1.

Referring to the drawing, I have shown a tube frame 10 having a tubular bar 11 which is preferably of rectangular cross section. The hanger or bracket 12 comprises two pressed metal parts which are welded together, one of them forming a spool bearing 13 and having a horizontal arm 14 to project inside the tube, and the other being the chain engaging arm 15 and having a lower arm 16 also extending into the tube. The upper end of the arm 15 is offset as at 17 to form a tongue which extends between the links 18 of the transporting chain. The spool S is supported by the bearing 13 and is provided with the usual colored tuft forming yarns not shown which project through the tuft tubes 19.

The arms 14 and 16 may have their left hand ends as viewed in Fig. 1 bent downwardly and upwardly, respectively, as at 20 and 21, and there may be located against the inner face of these ends a guide plate 22 slotted as at 23 to have sliding and guiding engagement with a tongue 24 around which is disposed a coil compression spring 25.

In carrying my invention into effect I form the arm 15 without a slot as suggested in Fig. 2, thereby strengthening the same so that it is stiffer than the chain engaging arms at present in use. A latch 30 is formed of a single piece of metal and has the upper end provided with an end shaped as a hook 31 to overlie one of the links 18. Extending

downwardly from the hook are two arms 32 and 33 which as viewed in Fig. 2 lie to the right and left, respectively, of the chain engaging arm. These arms define between them a slot 34 which is somewhat greater in width than the bearing 13.

The lower ends of the arms 32 and 33 are bent as shown in Figs. 1 and 2 to have upright portions 35 substantially parallel to the vertical walls of the bar 11. These arms are then bent inwardly to form a horizontal slide 100

bearing 36 from which projects the previously described tongue 24.

The tubular bar 11 is provided with a pair of horizontally aligning guide slots 37 through which the slide bearing 36 extends. These slots 37 extend to the end of the bar and form the support for the lower part of the hook.

In Fig. 1 there is illustrated part of an 10 unlocking clutch C. This clutch may be the same as that ordinarily employed except that the vertical wings 40 have a notch 41 cut in the upper left hand part thereof so positioned as to clear the previously described parts 35 of the arms 32 and 33 during the first part of the inward movement of the clutch. The notch, however, is defined in part by a wall 42 which will engage said part 35 as the clutch continues its inward movement. The lower part of the wing 40 may be of the usual width and engages the lower part of the tube frame to prevent swinging thereof.

In operation, the tube frames will be presented to tuft forming position as previously stated, after which the clutch C will move in toward the tube frame to cause the walls 42 to slide the latch longitudinally of the bar against the action of coil spring 25 and release the frame from the chain. During this movement the bearing will slide in the slots 37.

Fig. 3 sets forth the manner in which the hook may be removed. The plate 22 is removed, after which the arms 14 and 16 are spread apart slightly to assume the position shown in dotted lines so that the slide bearing 36 can pass between the bent ends 20 and 21. Because of the fact that the slot 34 is slightly larger than the bearing 13 the hook will slide over the latter without interference. It is to be understood that before the removing of the latch is undertaken the bracket will be removed from the tube frame by loosening the screws 43.

From the foregoing it will be seen that I have provided an improved tube frame hanger and latch wherein the chain engaging arm may be solid to have increased strength and wherein the hook is provided with two arms each of which may be as strong as the customarily employed latch. It will also be seen that the two arms are spaced so as to define an opening through which the bearing 13 can pass when the hook is being removed from the bracket for the purpose of renewal or repair.

Having thus described my invention it will be seen that changes and modifications may be made therein by those skilled in the art without departing from the spirit and scope of the invention and I do not wish to be limited to the details herein disclosed, but what I claim is:

1. In a tube frame for an Axminster loom

having a transporting chain, a carrier bar, a chain engaging arm projecting from the bar, a spool bearing arm also projecting from the bar, and a latch yieldably mounted on the bar and having spaced upright portions between which the arms lie, the upper part of the latch being formed as a hook to engage the chain, the space between the upright portions being large enough to pass the spool bearing.

2. In a tube frame for an Axminster loom 75 having a transporting chain, a carrier bar, a chain engaging arm projecting from the bar, a spool bearing arm also projecting from the bar, and a latch yieldingly mounted on the bar and surrounding portions of both of said arms and having holding engagement with the chain.

3. In a tube frame for an Axminster loom having a transporting chain, a carrier bar, a chain engaging arm projecting from the bar, a spool bearing arm also projecting from the bar, and a latch yieldingly mounted on the bar and having a slot therethrough in which a chain engaging arm normally lies and through which the spool bearing arm passes 90 when the latch is being removed.

4. In a tube frame for an Axminster loom having a transporting chain, a carrier bar, a chain engaging arm projecting from the bar, a spool bearing arm also projecting from the bar, and a latch yieldingly mounted on the tube frame and having the form of a closed loop in which the arms are located.

5. In a tube frame for an Axminster loom 200 having a transporting chain, a carrier bar, a chain engaging arm projecting from the bar, a spool bearing arm also projecting from the bar, a latch yieldingly mounted on the bar and having a tube frame supporting portion lying on each side of the chain engaging arm, and a chain engaging hook joining the supporting portions.

6. In a tube frame for an Axminster loom having a transporting chain, a carrier bar, a chain engaging arm projecting from the bar, a spool bearing arm also projecting from the bar, and a latch yieldingly mounted on the bar and having two tube frame supports, one lying on each side of the chain engaging arm, and a chain engaging hook joining the supports.

7. In a tube frame for an Axminster loom having a transporting chain, a carrier bar, a chain engaging arm projecting from the bar, a spool bearing arm also projecting from the bar, and a latch movably mounted on the tubular bar and having a vertically extending opening therethrough which is sufficiently large to slide over the spool bearing arm, the chain engaging arm projecting above the opening in the latch to engage a portion of and limit movement of the latch.

8. In a tube frame for an Axminster loom having a transporting chain, a carrier bar, a chain engaging arm projecting from the bar,

a spool bearing arm also projecting from the bar, and a latch movably mounted on the bar and having the upright portion thereof in the form of an elongated closed ring which surrounds the arms, the upper part of the latch engaging the chain and both sides of the ring supporting the tube frame.

9. In a tube frame for an Axminster loom having a transporting chain, a carrier bar, a chain engaging arm projecting from the bar, a spool bearing arm also projecting from the bar, two supporting members lying outside the chain engaging arm and having supporting relation with respect to the bar and having holding engagement with respect to the chain.

10. In a tube frame for an Axminster loom having a transporting chain, a carrier bar, a chain engaging arm projecting from the bar, a spool bearing arm also projecting from the bar, the chain engaging arm being solid and imperforate, and a tube frame supporting latch movably mounted with respect to the bar and having a pair of spaced members projecting substantially parallel to the chain engaging arm and held in supporting relation with respect to the chain.

11. In a tube frame for an Axminster loom having a transporting chain, a tubular bar having longitudinally extending slots therein, spool bearing and chain engaging arms fixed to the bar, and a latch to engage the chain and surrounding the part of the bar above said slots and extending through the latter into the bar, said latch being slidable in the slots.

12. In a tube frame for an Axminster loom having a transporting chain, a tubular bar having longitudinally extending slots therein, spool bearing and chain engaging arms fixed to the bar, a latch formed as a closed ring surrounding the chain engaging arm and having the lower part thereof extended into the bar through the slots and having sliding engagement with the latter, and a chain engaging hook on the latch yieldingly held over a portion of the chain.

13. In a tube frame for an Axminster loom operating with a transporting chain, a carrier bar, a chain engaging arm fixed to the bar, a latch movably mounted on the bar and surrounding the arm and having an opening therein, and a spool supporting arm also fixed to the bar and smaller than the opening in the latch, said latch being movable away from the chain engaging arm and over the spool supporting arm.

In testimony whereof I have hereunto affixed my signature.

OSCAR V. PAYNE.
